UNITED STATES PATENT OFFICE.

WILLIAM S. HAMM, OF CHICAGO, ILLINOIS, ASSIGNOR TO THE ADAMS & WESTLAKE COMPANY, OF ILLINOIS.

WASHSTAND.

SPECIFICATION forming part of Letters Patent No. 663,889, dated December 18, 1900.

Application filed October 30, 1899. Serial No. 735,170. (No model.)

To all whom it may concern:

Be it known that I, WILLIAM S. HAMM, a citizen of the United States, and a resident of Chicago, county of Cook, and State of Illinois, 5 have invented certain new and useful Improvements in Washstands, of which the following is a specification, and which are illustrated in the accompanying drawings, forming a part thereof.

10 The object of the invention is to provide an improved form of soap dish or holder for use in connection with a washstand of the type illustrated. This object is attained in the construction hereinafter fully described, 15 and which is shown in the accompanying drawings, in which—

Figure 1 is a plan view of the improved washstand. Fig. 2 is a vertical section on the line 2 2 of Fig. 1. Fig. 3 is a vertical section on the line 3 3 of Fig. 2.

The slab is shown as consisting of the sheet metal covering 10, the wood plate 11, and the lining 12, of felt or like material, interposed between these metal and wood parts. The 25 riser or splash-rail at the back of the stand is shown at 13, and at 14 is represented a side riser or splasher, and it will be understood that the sheet-metal covering 10 is carried up over the exposed surfaces of these 30 risers.

The bowl 15 is of any desired form and is secured to the slab in any desired manner.

There is shown in the drawings a valve-handle 22 fixed upon the stem 20 for controlling the water-supply, one of the water-pipes being shown at 16 as entering a valve-casing 18, the pipes leading from the valve-casing to the bowl 15 being shown at 23 24. There is also shown a handle 29 for controlling the 40 waste-valve, the stem of which is shown at 27 as being pivoted to the under side of the slab 11 at 28. As the water-supply and waste-valve form no part of the invention, I have not deemed it necessary to fully illustrate or 45 describe them.

The soap-dish is in the form of a box, comprising the members 30 and 31, the former of which is fitted within a suitable recess in the front face of the splasher 13 and the latter of 50 which is hinged to the lower edge of the mem-

ber 30, so that it may open downwardly and rest upon the upper surface of the slab. A spring-catch 32 retains the member 31 in its closed position. A drain-pipe 33 leads downwardly from the member 30 of the soap-dish 55 through the slab, and the lower portion of the member 30 of the soap-dish is perforated, as shown at 34, to permit drainage into this pipe. An apron 35, extending inwardly from the inner or lower edge of the member 31 of 60 the box, directs the drainage from this member into the waste-pipe 33. A finger 36, projecting backwardly and slightly upward from the apron 35, passes through a suitable slot in the wall of the member 30 of the box when 65 the member 31 is lowered and serves the purpose of moving the soap if it has a tendency to remain fast in the fixed member of the box, the purpose being to have the soap slide downward into the member 31 of the box 70 when it is lowered.

I claim as my invention—

1. In a washstand, in combination, a slab, a splasher-rail, a soap-box comprising a member 75 30, set within the front face of the splasher-rail, a member 31, hinged at the lower edge of the member 30, and a drain-pipe leading from the member 30, downwardly through the splasher-rail.

2. In a washstand, in combination, a 80 splasher-rail, and a soap-box comprising a member 30, set within the front face of the splasher-rail and having an opening near its lower edge, a member 31, hinged at the lower edge of the member 30, and having a backwardly-projecting finger for passing through the aperture thereof, substantially as and for the purpose specified.

3. In a washstand, in combination, a 85 splasher-rail, and a soap-box comprising a member 30, set within the front face of the splasher-rail, a drain-pipe leading from such member, a member 31, hinged at the lower edge of the member 30, and having a backwardly-projecting apron for leading to the 90 drain-pipe when the box is closed.

WILLIAM S. HAMM.
